CLAIM

The ornamental design for a head wrap, as shown and described.

DESCRIPTION

FIG. 1 is a front perspective view of a head wrap;

FIG. 2 is a front view thereof;

FIG. 3 is a rear view thereof; and,

FIG. 4 is a rear view of the head wrap shown in a position of use.

The broken line outline of the partial human figure in FIG. 4 assists in illustrating how the claimed design may appear when worn, but forms no part of the claimed design. The broken lines of the head wrap and the surface areas within the broken line areas define portions of the head wrap that form no part of the claimed design.
